 C. F. Burgess Laboratories, Inc., Chicago, Ill.,
 a corporation of Delaware

Application December 22, 1933, Serial No. 703,548

18 Claims. (Cl. 181—48)

This invention relates to improvements in silencers and particularly those used to silence the intakes and exhausts of internal combustion engines, compressors, pumps and the like. In particular, it relates to an improvement in the type of silencer disclosed and claimed in my copending application Serial No. 545,776, filed June 20, 1931 which includes means for attenuating sounds composed of both high and low frequencies.

In an exhaust system, gas pulses at high pressure and sounds are both present. Since sound is an alteration in pressure, or a super-position of a number of pressure alterations, propagated in an elastic medium, a sound propagated in gas or air may be called a gaseous pressure wave. It is an object of this invention to provide an improved silencer which attenuates gaseous pressure waves comprising both sounds and gas pulses of a wide range of frequencies. If the gas pulses are not attenuated or altered in form within the silencer, upon their emergence therefrom they expand into the atmosphere and create sounds. When the attenuation of sound is spoken of herein, it is meant to include the attenuation of gaseous pressure waves which would otherwise result in objectionable sounds being heard.

It is an object of this invention to provide an improvement in the construction of the low frequency attenuating means of such a silencer whereby the effectiveness thereof is increased.

It is a further object of this invention to combine and arrange the high frequency attenuating means with the low frequency attenuating means in such a manner that greatest possible effects are obtained from both for the size and/or quantity of attenuating means used.

It is a further object of the invention to provide an improved low frequency attenuating construction which may be used by itself, and which is particularly effective for exhausts, where gas pulses are involved.

By way of a brief statement of the principle of the present invention, in the silencers contemplated herein, the high frequency attenuating means usually comprises a wall of gaseous-pressure wave absorbing material along at least a portion of the passage through which the sounds travel through the silencer and the low frequency attenuating means comprises one or more space-volumes connected in side-branch relation to said passage. In such relation the space-volumes and their connection to the pas-

sage are called resonators and the space-volumes are called resonance chambers.

I have found that, if the communication between the passage and the space volumes, which may be called the entrance to the resonance chambers, or the neck of the resonators, is constructed in the form of an elongated slot opening extending longitudinally of the passage, low frequency attenuation is highly effective and that the effectiveness is most pronounced when gas pulses are present with the sounds to be silenced. If the entrance to the resonance chambers is of appreciable length, as by incorporating spaced lips or flanges along the longitudinal edges of the slot, the effectiveness of attenuation is further improved. The frequency for which the low frequency attenuating means is most effective can also be conveniently regulated in this manner. With an entrance of given dimensions, in order to attenuate sounds of predetermined frequency, a resonance chamber of a particular volume must be used. It has been found that if the resonance chamber is subdivided into a number of smaller chambers the attenuating effect is further improved. The present invention comprises the incorporation of these discoveries into a silencer to provide highly desirable improvements in attenuating characteristics.

In the drawings:

Fig. 1 is a longitudinal, sectional view of one form of the silencer of my invention along line 1—1 of Fig. 2;

Fig. 2 is a transverse, sectional view of the same structure along line 2—2 of Fig. 1;

Fig. 3 is a longitudinal, detail view of a portion of the conduit of the silencer of Figs. 1 and 2;

Fig. 4 is a transverse, sectional view along line 4—4 of Fig. 3;

Figs. 5, 6, and 7 are longitudinal, sectional views of modifications of the silencer of my invention;

Fig. 8 is a transverse, sectional view of the silencer shown in Fig. 7;

Fig. 9 is a longitudinal, sectional view of another form of the invention;

Fig. 10 is a transverse, sectional view of the silencer shown in Fig. 9;

Fig. 11 is a longitudinal, sectional view of another form of the invention;

Fig. 12 is a transverse, sectional view of a further modification;

Fig. 13 is a longitudinal, sectional view of another form of the invention;

Fig. 14 is a transverse, sectional view thereof; and

Figs. 15 through 22 are transverse views of conduits for my improved silencer showing 5 modifications of the means for providing communication between the conduit and the space-volumes or chambers.

The silencer shown in Figs. 1 to 4 consists of an imperforate outer shell or casing 1. The 10 casing is provided with end walls 2 and 3 having alined eccentric openings 4 and 5 respectively. A conduit 6 is disposed longitudinally within casing 1 and extends between openings 4 and 5. Its inlet end 4' and its outlet end 5' 15 extend beyond openings 4 and 5 respectively. Conduit 6 is provided with a longitudinal slot 7 which extends substantially the length of the conduit. In the use of the silencer, the direction of gas flow is substantially parallel to slot 7. 20 Flanges or lips 8 and 9 extend outwardly from the conduit along the longitudinal edges of slot 7 and are in spaced substantially parallel relation, being spaced apart by suitable means such as indents 10 (see Fig. 4), and held in such 25 spaced relation by suitable means such as spot welding at said indents.

In order to show the relative proportion of the slot dimensions to the rest of the silencer, the 30 dimensions of a successfully operating silencer will be given. In a silencer in which the casing 1 has an inside diameter of 5 inches and the conduit 6 an inside diameter of 1 $\frac{1}{4}$ inches, lips 8 and 9 extend 1 inch laterally outward from the periphery of the conduit and are spaced 35 $\frac{1}{2}$ inch apart. These dimensions may vary with silencers which are designed for different engines, but the space between lips 8 and 9 ordinarily should not be more than $\frac{1}{4}$ inch and usually ranges from $\frac{1}{8}$ to $\frac{1}{2}$ inch. The lips 40 may be of any suitable length but should not approach the interior walls of the shell 1 so closely as to restrict the free movement of sound and gas out of and into the conduit. The end portions of conduit 6 are foraminous as shown 45 at 11 and 12. The wall of that part of said conduit may be of screen, but it is preferred to make it of metal perforated with a large number of small holes. Lips 8 and 9 are preferably omitted at foraminous portions 11 and 12 50 of conduit 6, and slot 7 may also be omitted at these portions.

A plurality of lateral partitions 13 are arranged in longitudinally spaced relation along conduit 6 and extend between conduit 6 and casing 1 and are preferably welded in place. Partitions 13 divide the space between the casing and the conduit into a plurality of closed chambers 15. The partitions adjacent the end walls are preferably located at the boundary of the 60 perforated portions of the conduit. The end chambers thus formed surrounding perforated portions 11 and 12 of conduit 6 are filled with gaseous-pressure wave absorbing material 14, of the character described in the Schnell United 65 States Patent No. 1,811,762. The remaining chambers 15 are allowed to remain empty of such material.

For engine and compressor intakes, flammable absorbing materials such as cotton, wool, hair-felt, wood fiber and the like may be used whereas for gas engine exhausts and other hot gases, non-flammable absorbers should be used, such as steel wool and other metallic wool, exfoliated vermiculite, asbestos fibers, rock wool, pumice, 70 Haydite and other loose ceramic aggregates.

The aggregates may be bonded together in a manner so as to leave intercommunicating absorbing channels, as disclosed in Jack United States Patent No. 1,921,468.

In the acoustic action of the system, the 5 lipped slot or slots constitute the entrances or necks of the resonators. The neck of the resonator contributes acoustic inductance to the system and the volume contributes acoustic capacity. Regulation of these two factors determines 10 the frequency for which the system is most effective. Increasing the acoustic inductance, or the acoustic capacity, or both inductance and capacity lowers this frequency and decreasing these factors raises it. The acoustic inductance of 15 the resonator may be increased by reducing the transverse dimensions of the passage (preferably by narrowing the slot), or by increasing its length. The acoustic capacity may be increased 20 by increasing the volume of the chamber. 20

The chambers 15 surrounding conduit 6 act as expansion chambers or surge chambers for attenuating the gas pulses. The great length of slot 7 along the path of gas flow and the 25 concavity of the interior of conduit 6 allow a more ready flow of gas pulses from conduit 6 into the spaces surrounding it, than do the types of openings used heretofore. After the gas has expanded, the extreme thinness of passage 7 and 30 the convexity of the exterior of conduit 6 cause it to filter back into conduit 6 relatively gradually. In this manner the wide, slit-like passage acts as a trap which permits the ready flow of 35 gas out of the conduit but prevents its rapid return. Means will be described hereinafter for making this entrapping action more effective.

In silencers for both exhausts and intakes the 40 flow of gases or air through the silencer may create a high frequency, whistling sound. The section of gaseous-pressure wave absorbing material adjacent the outlet end of the silencer attenuates any such sound which may be created.

All the chambers shown in Fig. 1 are of the 45 same dimensions, but this is not essential and it may be found that a series of chambers each having a different length or volume is more effective for the particular engine with which the silencer is to be used. As explained here- 50 tofore, the dimensions of the slot and the lips along its edges and the volume of the chambers are factors which determine the frequency at which the low frequency attenuating section has its greatest effect, and they may be so proportioned as to attenuate sounds of any predetermined, objectionable bands of frequencies. 55

One method for broadening the frequency range of attenuation is to vary the length of the lips continuously from one end of the section to the other. For example, the length of the lips at the inlet end may be 1 $\frac{1}{4}$ inches and the length at the outlet end may be $\frac{3}{4}$ inch. Such an arrangement is shown in Fig. 5 which 60 illustrates a modification of the silencer shown 65 in Fig. 1. An imperforate casing or shell 31 is provided with end walls 32 and 33 having alined eccentric openings 34 and 35 respectively. A conduit 38 is disposed between openings 34 and 35. Its inlet and outlet ends 36 and 37, respectively, project beyond the corresponding ends of casing 31. The outlet end portion of conduit 38 is foraminous as shown at 39, and the remaining portion of conduit 38 has a longitudinal slot 40 therein. Lips 41 extend outwardly along 70 75

the edges of slot 40. Lips 41 are held in spaced relation and vary in length continuously, as shown, from one end of slot 40 to the other. The variation may be in stepped increments instead of continuous. A plurality of partitions 42 are mounted in longitudinally spaced relation between conduit 38 and casing 31 to form a plurality of chambers 43. The partition adjacent the outlet end of the silencer is mounted 10 on conduit 38 at the boundary of the foraminous portion 39 thereof. The chamber surrounding foraminous portion 39 of conduit 38 is filled with gaseous-pressure wave absorbing material 44. The size and number of empty chambers and 15 the size of the chamber filled with absorbing material may be varied to meet conditions encountered in various engines. The gas flow through the silencer may be reversed so that opening 35 serves as the inlet opening and 34 20 serves as the outlet opening. Two or more of the chambers 43 may be connected as by means of connecting tube 63 or by openings in partitions 42.

Fig. 6 illustrates a further modification of the 25 silencer shown in Fig. 1. In this modification a conduit 78 is located concentrically within a casing 79 and the chambers surrounding conduit 78 are substantially annular. The chamber of gaseous-pressure wave absorbing material 45 30 is located between two low frequency sound attenuating sections 46 and 47 in place of being located at one or both ends of the silencer as shown in Fig. 5 and Fig. 1 respectively. Lips 98 and 99 form passages from the slots in conduit 35 78 to the low frequency attenuating sections 46 and 47. The portions of lips 98 within one of the chambers of section 46 are omitted, said chamber being connected to the conduit by the slot only. The omission of said portions of lips 40 98 results in a change in the frequency range for which section 46 is effective.

In addition to its acoustic effect, the silencer exerts an effect upon the action of the gases passing therethrough. When the device is used 45 as an exhaust silencer pulses of exhaust gas of relatively great force emerge from the engine and enter the inlet opening of the silencer. The force of these pulses is reduced appreciably by the section of absorbing material adjacent the 50 inlet end of the silencer in Figs. 1 to 4. In some situations, the device of Fig. 1 has advantages over those of Figs. 5 and 6. In the latter constructions, the gas pulses, immediately upon entering the muffler, expand into the un- 55 occupied spaces of the first chambers. With pulses of sufficient magnitude it has been found that the gas expands into an unoccupied space with such force as to result in mechanical impact upon the casing, which creates a clinking 60 sound of high frequency which is audible from the exterior. With the device of Fig. 1 the force of the entering gas pulses is reduced sufficiently by the time they reach the following unoccupied chambers to prevent such action.

Figs. 7 and 8 illustrate a further modification 65 of the silencer of my invention. An imperforate casing or shell 16 is provided with end walls 17 and 18 having openings 19 and 20, respectively. Conduit 23 is arranged longitudinally within 70 casing 16 and connects openings 19 and 20. Its inlet and outlet ends 21 and 22 extend beyond the ends of casing 16. Conduit 23 is foraminous, preferably throughout its length, and has a longitudinal slot 24 therein which also extends 75 substantially the length thereof. Lips 25 extend

outwardly along the edges of slot 24 and are in spaced substantially parallel relation. An intermediate shell 26 is arranged in exterior spaced relation to conduit 23 and has a longitudinal slot 27 therein extending substantially the length 5 of shell 26. Slot 27 is aligned with slot 24 and the outer edges of lips 25 may be fastened along the edges of slot 27, as by spot welding. Lips 25 may extend beyond intermediate shell 26. The space between conduit 23 and intermediate 10 shell 26 is filled with gaseous-pressure wave absorbing material 28. When a molded gaseous-pressure wave absorbing material is used, it is possible to omit conduit 23 or intermediate shell 26 or both. A plurality of partitions 29 are arranged in longitudinally spaced relation between intermediate shell 26 and casing 16, forming a plurality of closed chambers 30. All of the chambers are shown in Fig. 7 to be of the same size, but the size and number of chambers may 15 be varied to suit conditions. This arrangement results in a very effective silencer since substantially the entire surface of conduit 16 is lined with absorbing material and a large volume 20 is still available for low frequency attenuation. 25

A further arrangement is illustrated in Figs. 9 and 10. An imperforate casing or shell 48 is provided with end walls 49 and 50 having aligned openings 51 and 52 respectively. Foraminous conduit 55 is disposed within casing 48 and connects openings 51 and 52. Its inlet and outlet ends 53 and 54 extend beyond the ends of casing 48. Conduit 55 is provided with a longitudinal slot 56 extending substantially the length of said conduit. Lips 57 extend outwardly along the 30 edges of slot 56 and are in spaced substantially parallel relation. A longitudinal partition 58 divides the cylindrical space within the casing 48 into two volumes. Fig. 10 shows these volumes to be substantially equal, but they may be 35 of different sizes as well. Partition 58 is provided with a longitudinal slot through which lips 57 may pass. The partition may be fastened to both casing 48 and lips 57 by suitable means such as spot welding. Conduit 55 is enclosed in 40 one of the volumes. The volume containing conduit 55 is filled with gaseous-pressure wave absorbing material 59. The remaining volume is divided into a plurality of closed chambers 60 by means of spaced lateral partitions 61. 50

Fig. 11 illustrates a construction in which the high frequency silencing means comprises a plurality of resonance chambers. The resonance chambers and the openings connecting them to the silencer conduit are so proportioned and arranged that they give satisfactory performance in attenuating the objectionable high frequency sounds. Casing 64 has end walls 65 and 66. A conduit 67 extends longitudinally through the casing. At the inlet and outlet ends of conduit 67 are arranged resonance chambers 68, connected to conduit 67 by relatively large openings 69. Resonance chambers 70 are arranged adjacent chamber 68 and connected to conduit 67 by openings 71. Chambers 68 and 70 and openings 69 and 71 are so proportioned and arranged that they attenuate the high frequency sounds in conduit 67. Between the high frequency attenuating sections formed by chambers 68 and 70, there are arranged a plurality of chambers 72. 70 These latter chambers are usually larger than the high frequency attenuating chambers. Chambers 72 are connected to conduit 67 by a slot opening 73 which may be provided with lips (not shown) extending into chambers 72. 75

Chambers 72 and slot 73 are so proportioned and arranged as to attenuate low frequency sounds in conduit 67. Two or more of the chambers 72 may be connected as by means of connecting tube 74 or by openings in partition 75 to provide series connected chambers.

A further modification of the silencer is illustrated in Fig. 12. An imperforate casing 100 is provided with end walls (not shown). This casing is shown oval or elliptical in transverse section, but it may be rectangular or other shape if desired. The interior of the casing is divided by longitudinal partitions 101 and 102, as shown. The partitions may be rigidly fastened to casing 100 by suitable means, such as spot welding. Longitudinal partitions 101 and 102 divide the casing into a number of volumes. The volumes between partition 101 and casing 100 and between partition 102 and casing 100 are filled with gaseous-pressure wave absorbing material 104. The remaining volumes 105 are allowed to remain empty of such material. Volumes 105 may be divided into a plurality of smaller volumes by means of lateral partitions (not shown), as hereinbefore described in connection with previous illustrations. The central volume 103 serves as a conduit for the passage of gas and gaseous-pressure waves through the silencer. The portions of partitions 101 and 102 which define conduit 103 are perforated, thereby exposing absorbing material 104 to the gaseous-pressure waves passing through the conduit. Portions 106 of longitudinal partitions 101 and 102 connect the central volume 103 with the volumes 105 which serve as resonators. The adjacent portions 106 may be held in spaced relation by indents (such as 10 in Figs. 3 and 4), and thus form the walls of the slit-like passages between conduit 103 and volumes 105.

Figs. 13 and 14 illustrate a further modification of the silencer in which the positions of the gas passage and the space volumes are reversed. An imperforate casing 107 is provided with end walls 108 and 109 having openings 110 and 111, respectively. Openings 110 and 111 are adapted to receive inlet duct 110' and outlet duct 111', respectively. An inner shell 112 is arranged longitudinally within casing 107 and is held in spaced relation thereto by means of spacing members 113. Shell 112 is provided with end walls 114 and 115. The gases pass through the annular duct formed between the casing and the shell. The ends of shell 112 may be conical, if desired, to minimize resistance to the flow of gas through the silencer. The end walls 114 and 115 and the end portions of the side walls of shell 112 are perforated, the remaining portion of the shell having a longitudinal slot 119 therein. Lips 120 extend inwardly along the edges of slot 119 and are maintained in spaced relation. A plurality of partitions 116 are arranged in longitudinally spaced relation within shell 112 to form a plurality of closed chambers 117. The partitions adjacent the end walls 114 and 115 are preferably located at the boundary of the perforated portions of the shell. The volumes thus formed adjacent the end walls are filled with gaseous-pressure wave absorbing material 118. The remaining chambers are allowed to remain empty of such material. The perforated portions of shell 112 thus contain the gaseous-pressure wave absorbing material and lipped slot 119 provides entrance to unoccupied chambers 117.

Figs. 15, 16, and 17 illustrate modifications of

the form of the passage between the conduit and the space-volumes. As shown in Fig. 15, a conduit 80 is provided with two oppositely disposed longitudinal slots 81 having spaced outwardly extending lips 82 along the edges of the slots. The lips at one side of conduit 80 project radially while those at the other side project at an angle.

In Figs. 1 to 14, inclusive; the lips along the edges of the slots have been shown as being in substantially parallel spaced relation. The lips may also diverge slightly as they proceed outwardly from the conduit, as shown at 83, in Fig. 16. This arrangement has the advantage of promoting the ease of passage of the gas pulses into the space volume surrounding the conduit.

The lips may also converge, as shown at 84 in Fig. 17. This arrangement increases the effectiveness of the entrapping action exerted by the lips upon the gases and increases the resistance to the return of the pulsations of gas to the conduit while it still does not prevent its return flow in the form of a more or less steady stream.

The divergence and convergence of lips 83 and 84 of Figs. 16 and 17, respectively, are not so abrupt as to change the character of the passage formed between them from a passage having length to a mere orifice. The difference between the small transverse dimensions at the inlet and outlet ends of the passage should be not more than about $\frac{1}{8}$ inch and preferably is about $\frac{3}{16}$ to $\frac{1}{16}$ inch.

The length of the passage may be increased by arranging baffles 87 adjacent and exteriorly of lips 86 as shown in Fig. 18. A single passage is formed between lips 86 and a double passage is formed from the ends of lips 86 to the volume within casing 88.

The acoustical characteristics may be further varied by providing a double passage as shown in Fig. 19. In this case baffle 89 is arranged between lips 90. Such a passage tends to increase the width of the band of frequencies attenuated.

A double passage may be provided by means of the arrangement shown in Fig. 20. In this form lips are not provided in attached relation to the longitudinal edges of slot 91. A mere slot opening is provided. An arcuate baffle 92 is arranged in substantially parallel spaced exterior relation to conduit 93 and extends longitudinally thereof with its mid portion opposite the slot opening 91. Baffle 92 may be supported by the ends of casing 94 or at intervals along the length of conduit 93.

The entrance to the space volumes may also be provided by forming the conduit with its portions 95 adjacent the longitudinal edges (which normally form the seams), arranged in spaced overlapping relation as shown in Fig. 21. The length of overlap may be varied as desired. Spacing members or indents, similar to indents 10 (see Figs. 3 and 4) may be employed to properly space the overlapped portions 95. Overlapping portions 95 may be considered to be the lips upon the edges of the slot opening, or the exterior portion 95 may be considered to be a baffle similar to baffle 92 of Fig. 20.

Fig. 22 illustrates a further modification which provides length for the passage into the space volume without necessitating excessive radial projection of the lips from the conduit. Lips 96 and 97 are spaced from each other in the ordinary manner, but lip 96 is considerably longer than lip 97 and turns backward beyond the end 75

of lip 97 to provide successive lengths of the passage on opposite sides of lip 97.

Other changes in design may be made. The size and number of closed chambers may be varied to meet the requirements of a particular engine. The partitions within the casing need not be perpendicular to the conduit and casing, but may be placed at an angle other than 90°. The slot opening may vary in width at points along its length. The slot opening may be made discontinuous. Each chamber may be provided with an individual slot opening in the conduit. The slot opening may be of a length less than that of the chamber.

15 I claim:

1. A silencer for attenuating sounds composed of both high and low frequencies comprising a substantially imperforate casing having openings in the ends thereof, a conduit for the sound to be silenced within said casing extending between said openings, and spaced partitions between said casing and said conduit dividing said casing longitudinally into a plurality of closed chambers, the chambers adjacent the ends of said casing being filled with gaseous-pressure wave absorbing material, the portions of said conduit surrounded by said absorbing material being perforated, the portions of said conduit surrounded by said unoccupied chambers having a longitudinal slot therein, spaced substantially parallel lips upon the longitudinal edges of said slot projecting exteriorly of said conduit, the total length of slot opening connecting said conduit with said unoccupied chambers being not more than twice the total longitudinal length of said unoccupied chambers.

2. Apparatus for silencing sounds comprising in combination, a conduit for the sound to be silenced, a series of closed chambers disposed longitudinally of and surrounding said conduit, the end chambers of said series being filled with gaseous-pressure wave absorbing material, the portions of said conduit surrounded by said absorbing material being foraminous, the intermediate chambers of said series being unoccupied and defining closed space-volumes, the portion of said conduit surrounded by said intermediate chambers having a longitudinal slot therein, and substantially parallel lips upon the longitudinal edges of said slot and projecting into said intermediate chambers, the total length of slot opening connecting said conduit with said unoccupied chambers being not more than twice the total longitudinal length of said unoccupied chambers.

3. A silencer for attenuating sounds composed of both high and low frequencies, comprising a conduit for the sounds to be silenced, a series of closed chambers disposed longitudinally of and surrounding said conduit, said conduit having a longitudinal slot therein communicating with the interior of said chambers, spaced lips upon the edges of said slot and projecting into said chambers, the total length of slot opening connecting said conduit with said unoccupied chambers being not more than twice the total longitudinal length of said chambers, and high frequency attenuating means surrounding said conduit at the ends of said series of chambers.

70 4. A silencer for attenuating sounds composed of both high and low frequencies comprising a substantially imperforate casing having openings in the ends thereof, a conduit for the sound to be silenced within said casing extending between said openings, spaced partitions between said

casing and said conduit dividing said casing longitudinally into a plurality of closed chambers, and gaseous-pressure wave absorbing material arranged in some of said chambers, the portions of said conduit surrounded by said absorbing material being perforated and a longitudinal slot in said conduit connecting said conduit with said unoccupied chambers, the total longitudinal length of said slot opening connecting said conduit with said unoccupied chambers being not more than twice the total longitudinal length of said unoccupied chambers.

5. A silencer for attenuating sounds composed of both high and low frequencies comprising a conduit for the sound to be silenced, a series of closed chambers disposed longitudinally of and surrounding said conduit, gaseous-pressure wave absorbing material arranged in some of said chambers, the portions of said conduit surrounded by said absorbing material being foraminous, others of said chambers comprising closed space-volumes, the portions of said conduit surrounded by said space-volumes having longitudinal slots therein connecting said chambers with said portions of said conduit, and substantially parallel lips upon the longitudinal edges of said slots and extending exteriorly of said conduit the total longitudinal length of the slot opening connecting said conduit with said unoccupied chambers being not more than twice the total longitudinal length of said unoccupied chambers.

6. A silencer for attenuating sounds composed of both high and low frequencies comprising a conduit for the sounds to be silenced, high frequency attenuating means surrounding a portion of said conduit, a series of closed chambers disposed longitudinally of and surrounding a further portion of said conduit, said portion of said conduit surrounded by said closed chambers having a longitudinal slot therein, and spaced lips along the longitudinal edges of said slot and projecting exteriorly of said conduit the longitudinal length of the slot opening connecting said closed chambers to said conduit being substantially equal to the total length of said closed chambers.

7. A silencer for attenuating sounds composed of both high and low frequencies comprising a substantially imperforate casing having openings therein, a conduit for the sound to be silenced within said casing and connecting said openings, a layer of gaseous-pressure wave absorbing material exposed in the walls of said conduit, said conduit having a longitudinal slot therein, and spaced partitions within said casing, dividing at least a portion of said casing into a plurality of space-volumes, said space-volumes being connected in side-branch relation to said conduit by means of said slot, the total longitudinal length of slot opening connecting said space-volumes to said conduit being not more than twice the total longitudinal length of said space-volumes.

8. A silencer for attenuating sounds composed of both high and low frequencies comprising a conduit for the sounds to be silenced, a gaseous-pressure wave absorbing wall for at least a portion of said conduit, said conduit having an elongated opening extending longitudinally thereof, spaced, outwardly extending lips along the longitudinal edges of said opening, and at least one closed chamber in communication with said conduit by means of said opening, the total longitudinal length of slot opening connecting

said closed chamber to said conduit being not more than twice the total longitudinal length of said closed chamber.

9. A silencer for attenuating sounds composed of both high and low frequencies comprising a conduit for the sounds to be silenced having high frequency attenuating means associated with at least a portion of the wall of said conduit, and a closed chamber disposed longitudinally of and adjacent to said conduit, said conduit having an elongated slot extending longitudinally thereof, said slot providing communication between said conduit and said closed chamber, the total longitudinal length of slot opening connecting said closed chamber to said conduit being not more than twice the total longitudinal length of said closed chamber.

10. A silencer comprising a substantially imperforate casing, a conduit for the sound to be silenced extending through said casing, gaseous-pressure wave absorbing material substantially surrounding said conduit and exposed in the walls thereof, said absorbing material partially filling said casing, said conduit and absorbing material having coinciding slots therein extending longitudinally thereof, said slot providing communication from said conduit to the space in said casing.

11. A silencer comprising a substantially imperforate casing, a partition extending longitudinally of said casing dividing said casing into two chambers, a filling of gaseous-pressure wave absorbing material in one of said chambers, the other chamber constituting a space volume, a conduit for the sounds to be silenced passing through said filled chamber, said absorbing material being exposed in the walls of said conduit, said conduit having an elongated slot therein extending longitudinally thereof, and spaced lips along the longitudinal edges of said slot, said partition and said absorbing material having openings therein coinciding with said slots, said lips extending through said openings and providing communication between said conduit and said space volume.

12. A silencer comprising a substantially imperforate casing having openings in the ends thereof, a partition extending longitudinally of said casing dividing said casing into two chambers, a filling of gaseous-pressure wave absorbing material in one of said chambers, the other chamber constituting a space volume, a conduit for the sounds to be silenced passing through said filled chamber, said absorbing material being exposed in the walls of said conduit, said conduit having an elongated slot therein extending longitudinally thereof, spaced lips along the longitudinal edges of said slot, said partition and said absorbing material having openings coinciding with said slots, said lips extending through said openings and providing communication between said conduit and said space volume, and lateral partitions spaced longitudinally within said space volume, subdividing said space volume into a plurality of smaller space volumes.

13. In a silencer comprising a conduit providing a through passage for the sounds to be silenced, a closed chamber disposed adjacent said passage, said conduit having an elongated slot opening therein extending longitudinally thereof and connecting said closed chamber in side

branch relation to said conduit and at least one plate disposed adjacent said slot and exteriorly of said conduit and extending longitudinally of said conduit, said plate forming a passage of slit-like lateral dimensions between said slot opening and said closed chamber, the total longitudinal length of slot opening connecting said closed chamber to said conduit being not more than twice the total longitudinal length of said closed chamber.

14. A silencer comprising a conduit providing a through passage for the sounds to be silenced and the gases passing therethrough, a closed chamber disposed adjacent said conduit, said conduit having an elongated slot opening therein extending in the direction of gas flow, and spaced lips along the edges of said slot and forming a passage of slit-like lateral dimensions connecting said conduit with said closed chamber in side-branch relation to said conduit, the total longitudinal length of slot opening connecting said closed chamber to said conduit being not more than twice the total longitudinal length of said closed chamber.

15. In a silencer comprising a through type passage for the sounds to be silenced, a conduit comprising said passage, a plurality of closed chambers disposed longitudinally along and surrounding said conduit, said conduit having an elongated slot therein extending longitudinally thereof, and spaced lips upon the longitudinal edges of said slot, said slot and lips forming a passage of slit-like lateral dimensions connecting said conduit and said chambers in side branch relation, the total longitudinal length of slot opening connecting said closed chambers to said conduit being not more than twice the total longitudinal length of said closed chambers.

16. In a device of the class described, a conduit comprising a through passage, a closed chamber adjacent said passage, said conduit having an elongated slot therein extending longitudinally thereof and connecting said closed chamber in side branch relation to said conduit, and spaced lips upon the longitudinal edges of said slot and projecting exteriorly of said conduit, said lips converging gradually as they proceed away from said conduit.

17. In a silencer comprising a conduit providing a through passage for the sounds to be silenced and the gases passing therethrough, and a closed chamber disposed adjacent said conduit, said conduit having an elongated slot opening therein extending in the direction of gas flow, said slot opening connecting said closed chamber in side-branch relation to said conduit, the total length of slot opening being not more than twice the total length of said closed chamber.

18. In a silencer comprising a conduit providing a through passage for the sounds to be silenced and the gases passing therethrough, and a closed chamber disposed adjacent said conduit, said conduit having an elongated slot opening therein extending in the direction of gas flow, said slot opening connecting said closed chamber in side-branch relation and having a length substantially equal to the length of said closed chamber.
